UNITED STATES PATENT OFFICE.

NEWTON H. SMITH, OF HAMILTON, ILLINOIS, ASSIGNOR OF ONE-HALF TO WILLIAM C. HOWELL, OF KEOKUK, IOWA.

EARTH-BORING TOOL.

1,269,970.

Specification of Letters Patent. Patented June 18, 1918.

Application filed May 20, 1916. Serial No. 98,832.

To all whom it may concern:

Be it known that I, NEWTON H. SMITH, a citizen of the United States, residing at Hamilton, in the county of Hancock and 5 State of Illinois, have invented a new and useful Earth-Boring Tool, of which the following is a specification.

This invention relates to earth boring tools primarily designed for use in boring 10 into the ground so as to permit the laying of gas pipes or small water pipes without the necessity of digging excavations.

Earth boring tools of this character as heretofore devised have been objectionable 15 for the reason that the auger used has loosened the dirt and, after the tool has been forced a certain distance through the ground, it has been necessary to withdraw it for the purpose of removing the loosened 20 dirt engaged by the auger. Because of this necessary removal of the auger, the boring operation has been hard and tedious, particularly where bores of considerable length were to be produced. One of the objects 25 of the present invention is to provide a tool of this character having a disk designed to loosen the soil and which disk may be extended from a feed screw preferably tapered toward its front end and which screw serves 30 to pack the soil outwardly, thus densifying the wall of the bore and gradually increasing the diameter of said bore so that the operation of the tool can be continued as long as no unyielding obstruction is encountered, friction being reduced materially and 35 the displaced soil being taken care of by packing rather than by removing it.

A further object is to provide the tool with antifriction packing devices which 40 operate to press the walls of the bore outwardly during the rotation of the tool in one direction but which automatically retract when the rotation of the tool is reversed, so that said tool can be easily re- 45 moved.

With the foregoing and other objects in view which will appear as the description proceeds the invention resides in the combination and arrangement of parts and in 50 the details of construction, hereinafter described and claimed, it being understood that changes in the precise embodiment of the invention herein disclosed, can be made within a scope of what is claimed, without departing from the spirit of the invention.

In the accompanying drawings the pre-

ferred form of the invention has been shown.

In said drawings:

Figure 1 is a side elevation of the soil 60 engaging portion of the tool.

Fig. 2 is an enlarged section on line A—B Fig. 1.

Fig. 3 is an enlarged longitudinal section on line C—D Fig. 1 and showing the anti-friction packing rollers shifted to their active positions.

Fig. 4 is a section on line E—F Fig. 3.

Referring to the figures by characters of reference 1 designates a tapered feed screw 70 to the small end of which is connected a bit 2. Extending from the large end of the screw is a tapered reamer including a body 3 provided with longitudinal ribs 4 the advancing faces of which are eccentrically disposed as indicated at 5 and curved gradually outwardly to the extreme edges 6 of the ribs, the back faces of the ribs being concaved abruptly as indicated at 7 and merging into the convex faces of the adjoining ribs. Thus 80 it will be seen that when the tool is rotated in a clockwise direction, these cam faces of the ribs will act as packing elements for pressing outwardly against the wall of the bore in which the tool is located. As the 85 reamer is slightly tapered, during the longitudinal movement of the tool this packing action will be continuous.

Connected to the rear end of the reamer body 3 is a core 8 consisting of a central 90 portion 9 concentric with the axis of rotation of the tool and end portions 10 and 11 which are eccentrically disposed relative to the longitudinal axis of the tool, the two end portions 10 and 11 being offset in opposite directions from the axis. On each of these eccentric portions of the core is mounted an eccentric bearing sleeve 12 designed, when rotated to one position upon its core, to lie with its outer face concentric with 100 the axis of rotation of the tool but, when this sleeve is moved away from such position, as during the clockwise movement of the core within the sleeve, said sleeve is gradually shifted to an eccentric position 105 until it has completed a one half revolution. The movement of the sleeve relative to the core is limited by a stud 13 extending into a groove 14 formed within the sleeve and extending approximately half-way around 110 the sleeve or any other desired means can be used for this purpose.

- On each of the bearing sleeves is mounted a roller 15, this roller obviously shifting with the sleeve into or out of eccentric position. When the two rollers are in their 5 positions concentric with the axis of rotation of the tool, they obviously align with each other and approximately with the rear end of the reamer body. When, however, said rollers are shifted to their eccentric 10 positions, due to the clockwise rotation of the core within the bearing sleeve 12, they will shift outwardly beyond the body of the reamer so that the rollers will press against the walls of the bore at diametrically opposed points. If desired, a roller 16 may be mounted upon the central or concentric portion of the bore 9, the diameter of this roller being the same as that of the rollers 15. A rod 17 is adapted to be connected to the 15 rear end of the core 8 and it is to be understood that this rod can be made up of sections designed to be coupled together as necessary.

In using the tool, the bit 2 is forced into 25 the ground to loosen the soil and the screw 1 follows after it. The other parts of the tool are drawn along by the screw as will be obvious. The screw 1, being tapered, serves to press the soil outwardly. Any 30 soil remaining between the threads of the screw will pass between the ribs on the reamer and as this reamer is rotating in a clockwise direction, the cam-faces 5 thereof will press the loosened soil outwardly and 35 pack it in the wall of the bore, thus densifying the wall and making it smooth and hard.

After the ribs of the reamer have acted 40 upon the wall of the bore, the packing rollers 15 come into action. When the rollers 15 are in engagement with the wall of the bore the eccentric bearing sleeves during the rotation of the tool in a clockwise direction, will be shifted from their concentric to their 45 eccentric positions and, consequently, the rollers 15 will be shifted outwardly out of line with each other. Thus the rollers will press against the wall of the bore and will roll therealong, completing the packing operation and also reducing friction.

Should it be desired to withdraw the tool 55 from the bore, it would merely be necessary to rotate it in a counter clockwise direction. Thus the bit and the screw would unscrew from engagement with the soil and the rollers 15 would be partly or entirely retracted. As the diameter of the bore would be somewhat greater than the greatest diameter of the reamer 3, the ribs 14 would not seriously 60 break down the wall of the bore during this removal.

While rods can be used for forcing the tool through the ground, it is to be under-

stood that if preferred, the pipe sections to be laid can be coupled to the tool so that 65 after the tool has been forced through the ground and has been brought to the extreme position to which the pipes are to be extended, said pipes will be in position without any further operation.

Under some conditions either the rollers 70 15 or the reamer 3 can be dispensed with.

While the tool herein described is particularly designed for use in laying pipes, it is to be understood that the same can be 75 employed advantageously wherever it is desired to produce an opening in the ground for any purpose.

What is claimed is:—

1. A tool of the class described including 80 a boring element, packing rollers coupled to the boring element, means for automatically shifting the rollers to eccentric positions relative to the axis of rotation of the tool during the rotation of said tool in a 85 clockwise direction and for retracting the rollers to concentric positions during the counter clockwise movement of the tool.

2. An earth boring tool including an 90 auger, a core revoluble therewith and having oppositely offset eccentric portions, a sleeve mounted for rotation upon each of said offset portions, said sleeves having eccentric core receiving openings, means for 95 limiting the rotation of the sleeves, said sleeves being concentric with the axis of rotation of the core when at one limit of their movement and eccentric thereto when at the other limit of their movement, and packing rolls mounted for rotation upon 100 the sleeves.

3. An earth boring tool including a tapered auger, a bit at the small end thereof, and smooth faced packing and smoothing rollers revolvable with the auger and shiftable into and out of eccentric positions relative to the axis of rotation of the tool.

4. An earth boring tool including a boring element, and means revolvable with said element for enlarging the bore and packing 110 and smoothing the wall thereof, said means including a core having oppositely offset eccentric portions, sleeves mounted for rotation on said portions and having eccentric openings in which the core is mounted, 115 means for limiting the rotation of the sleeves to and from eccentric positions, and smooth faced rollers of uniform diameter mounted for rotation on the sleeves.

In testimony that I claim the foregoing 120 as my own, I have hereto affixed my signature in the presence of two witnesses.

NEWTON H. SMITH.
